UNITED STATES PATENT OFFICE.

LOUIS J. LUDWIG, OF PHILADELPHIA, PENNSYLVANIA.

HEDDLE-DISCONNECTING MEANS FOR PLUSH LOOMS.

Application filed July 10, 1924. Serial No. 725,141.

To all whom it may concern:

Be it known that I, LOUIS J. LUDWIG, a citizen of the United States, residing at Philadelphia, in the county of Philadelphia and State of Pennsylvania, have invented certain new and useful Improvements in Heddle-Disconnecting Means for Plush Looms, of which the following is a specification.

10 My invention relates to plush looms and more particularly to the means for operatively disconnecting the heddles.

Plush fabric consists of a backing having an interwoven and evenly cut pile or nap. 15 The fabric coming from the loom consists of a pair of backings connected by interwoven uncut pile or nap threads. This double fabric is passed through a splitting machine which cuts the pile threads midway between 20 the backings. The ends of the double fabric are woven partway, without the pile threads, between the backings. These ends, known as headings, are for interlocking the pile threads between the woven threads of the 25 headings to make a finished end and for attaching the double fabric to spike rolls in the splitting machine so that when the double fabric is split, one piece of plush will be rolled up on one roll and the other piece on 30 another roll. Before weaving the headings, the pile weaving mechanism must be disconnected.

The usual practice is to disconnect the pile heddles from their straps, when the heddles 35 are midway of their path of travel, and to tie or otherwise support them on the frame in this position.

The objection to this method is that it requires considerable time; that it requires an 40 experienced person to properly disconnect and connect the heddles; that the weaver loses time in waiting for the proper person to make the disconnection, and that the weaving mechanism is idle meantime.

45 The objects of my invention are to provide means on the pile heddle moving means whereby a quick operative connection and disconnection of the heddles may be made by an inexperienced person and to so mount 50 the heddle-moving means that access thereto may be readily had.

These objects, and other advantageous ends which will be described hereinafter, I attain in the following manner, reference 55 being had to the accompanying drawings in which—

Figure 1 is a front view of a loom embodying my invention, certain parts being omitted,

Figure 2 an enlarged fragmentary left 60 side view of the loom shown in Figure 1,

Figure 3 a view similar to Figure 2 but illustrating the parts in another position,

Figure 4 a central section through elements which form a part of my invention, 65

Figure 5 a section on line 5—5 of Figure 4, and

Figure 6 a right side view of Figure 5.

Briefly the invention consists in loosely mounting the cams for operating the pile 70 heddles on the drive shaft; providing manually operated means for connecting and disconnecting the shaft and the cams; disposing all of the heddle operating cams outside the loom frame, and connecting the cams 75 with the tops of the heddles.

Referring to the drawings, 1 indicates the loom frame provided with top pulleys 2 and bottom pulleys 3. Heddles 4 are supported by the pulleys and operated by heddle moving mechanism 5 connected with the tops of the heddles.

The first pair of heddles from the right is for shifting the pile threads and is indicated by P. The second pair is for shifting the top backing threads and is indicated by B. The third pair is for shifting the bottom backing threads and is indicated by B'. The mechanism which shifts these heddles consists of a driving shaft 6 mounted 80 in the frame; four backing cams 7 fixed to the shaft; four backing levers 8 pivoted at 9 and provided with rollers 10 adapted to engage backing cams 7; a pair of pile cams 11 loosely mounted on shaft 6, and a pair of pile levers 12, also pivoted at 9, provided 85 with rollers 13 adapted to engage pile cams 11. Each free end 14 of levers 8 and 12 is connected to one of the heddles by a rod 15, a chain 16 passing over a pulley 2, a pair of wire rods 17, a pair of straps 18 passing 90 over the other pulleys 2 and a pair of hooks 19 secured to the heddles adjacent their ends. The connections between the parts 15, 16, 17, 18 and 19 may be made in any suitable manner. The pairs of heddles P, B and 95 B' are connected at their bottoms, adjacent the ends, by a pair of hooks 20, a pair of straps 21 passing around the bottom pulleys 3 and hooks 22 secured to the adjacent heddle.

A manually operated lever 23 pivoted at 110 24 is connected for operating clutching

means 25 which are adapted to connect the loosely mounted pile cams 11 with shaft 6. Clutching means 25 is of such character that the loosely mounted cams 11 will be connected to driving shaft 6 in the same relative position at all times, thereby insuring proper timing of the pile heddles relatively to the other parts of the loom and making the heddle disconnecting means fool-proof. I 10 have shown clutching means 25 as consisting of a single dog clutch member 26 fixed to cams 11 and a single dog clutch member 27 slidably keyed on shaft 6 and provided with an annular groove 28 for receiving a 15 block 29 pivoted at opposite sides of lever 23. Lever 23 is held in clutching and non-clutching position by a locking arm 30, pivoted to the lever and having a notch adapted to hook over a pin 33 on the loom frame to hold lever in clutching position, and a notch 34 adapted to engage pin 33 to hold the lever in non-clutching position. These notches insure that the clutching means 25 will always be either in clutching or non-clutching position.

During the weaving of the double backing plush the shifting of the top backing heddles B takes place above the shifting movement of the bottom backing heddles B' 30 and the shifting movement of the pile heddles P is from the uppermost position of the top backing heddles B to the lowermost position of the bottom backing heddles B'.

When it is desired to weave a heading in 35 the cloth, pile heddles P are brought to the center of their path of movement as shown in Figure 3. If the pile heddles are now disconnected from the heddle operating mechanism and the backing heddles are allowed to operate in the usual manner, the cloth produced will consist of a top backing and bottom backing with the pile threads floating between the backings instead of being interwoven. The pile heddles are therefore 40 disconnected from the heddle operating mechanism by manipulating holding arm 30 and lever 23 to disconnect clutching member 27 from member 26, and bring notch 34 on pin 33 to hold the lever in this non-clutching position. The loom is then operated in the usual manner and the top and bottom backings are woven with the pile threads floating between the backings. During the weaving action, cams 11 and the parts between the cams and the pile heddles 45 will remain idle, while cams 7 and the mechanism between the cams and the backing heddles will operate in the usual manner.

With the mechanism above described, the 50 pile weaving mechanism may be instantaneously connected or disconnected by merely actuating a lever.

While I have described my invention as 55 taking a particular form, it will be understood that the various parts may be changed

without departing from the spirit thereof, and hence I do not limit myself to the precise construction set forth, but consider that I am at liberty to make such changes and alterations as fairly come within the scope 70 of the appended claims.

Having thus described my invention, what I claim as new and desire to secure by Letters Patent is:—

1. In a loom having pile heddles and backing heddles, a driving shaft, pile cams loosely mounted on said shaft and operatively connected with the pile heddles, other cams fixedly mounted on said shaft and operatively connected with the backing heddles, a 75 clutching member on the pile cams, another clutching member slidably mounted on the shaft to rotate therewith, and a hand operated lever engaging said slideable clutching member for moving it at will into and out of clutching engagement with the member on the cams.

2. In a loom having pile heddles and backing heddles, a driving shaft, pile cams loosely mounted on said shaft and operatively connected with the pile heddles, other cams fixedly mounted on said shaft and operatively connected with the backing heddles, a clutching member on the cams, another clutching member slidably mounted 90 on the shaft to rotate therewith, a hand operated lever engaging said slideable clutching member for readily moving it at will into and out of clutching engagement with the clutching member on the cams, and a latch for holding the lever in clutching and in non-clutching position.

3. In a loom having a frame provided with top and bottom pulleys, pile heddles and backing heddles and a shaft for operating the heddles mounted in the frame, pile cams loosely mounted on said shaft and operatively connected with the pile heddles, other cams fixedly mounted on the shaft and operatively connected with the backing heddles, a lever pivoted at one end and having means at its intermediate end for engaging each cam, flexible means connected with the free end of each lever, passing over the top pulleys of the frame and connected with the top of each heddle adjacent its ends, flexible means connected to the bottom of each heddle adjacent its ends, to pass around the bottom pulleys and connected to the bottom of the adjacent heddle 110 near its ends, a clutching member on the pile cams, another clutching member slideable on the shaft to rotate therewith, and a hand operating lever to engage said slideable clutching member to move it into and out of clutching engagement with the member on the cam.

In testimony whereof I have signed my name to this specification.

LOUIS J. LUDWIG.
